UNITED STATES PATENT OFFICE.

MARY V. CLARK, OF WESTMORELAND, WEST VIRGINIA.

BUST CONFINING AND REDUCING GARMENT.

1,197,344.

Specification of Letters Patent.

Patented Sept. 5, 1916.

Application filed April 10, 1916. Serial No. 90,174.

To all whom it may concern:

Be it known that I, MARY V. CLARK, a citizen of the United States, residing at Westmoreland, in the county of Wayne and 5 State of West Virginia, have invented new and useful Improvements in Bust Confining and Reducing Garments, of which the following is a specification.

My present invention pertains to body 10 garments of the bust reducing type; and it has for its object to provide a simple, easily-donned and adjusted garment, adapted to serve efficiently as a bust confiner and reducer and also as a corset cover, with a view 15 to improving the figure and appearance of the wearer.

Other objects and advantageous features 20 of the invention will be fully understood from the following description and claim when the same are read in connection with the drawings, accompanying and forming part of this specification, in which:

Figure 1 is a perspective showing the 25 novel garment in use. Fig. 2 is a rear perspective of the garment, removed.

Similar numerals of reference designate corresponding parts in both views of the drawings.

My novel garment comprises a body portion 30 1, formed in one piece of thin textile or other suitable material; shoulder straps or tapes 2, permanently joined at their ends to said body portion; fastening straps or tapes 3 also permanently joined to the body portion; an elastic connection 4 interposed between the ends of the tabs on the body portion 1 at the back and upper end of the garment and calculated to lend the requisite elasticity to the upper portion of the same.

The front and sides of the body portion 1 40 are preferably of even height, and the front is preferably, though not necessarily, provided on the lower part of its vertical center with a reinforcement in the form of a tape 5. The sides of the said body portion merge 45 into upper back tabs 6 and lower back tabs 7; the upper and lower tabs being separated by intervening space of general V-shape, so that the lower edges of the upper tabs are inclined upwardly, and the upper 50 edges of the lower tabs are inclined downwardly. The elastic connection 4 is preferably in the form of two sections of elastic webbing as illustrated; the said connection 55 being permanently joined in approved man-

ner to the ends of the upper tabs 6. The lower back tabs 7 of the body portion carry the fastening straps or tapes 3, which are of such length that they can be drawn taut and tied together at the front of the wearer. 60

My novel garment is especially designed for fat women, and in practice it is slipped over the head and drawn down and around the body, and is then fastened through the medium of the straps or tapes 3. When the 65 garment is thus applied, it forces the breasts downwardly and compresses or confines the same, and in that way improves the figure and general appearance of the wearer. I would also have it understood that when applied as stated, my novel garment confines and covers the fat which overhangs the corset at the back, and in that way hides such fat when a thin blouse is worn.

The elastic connection 4 serves incidental 70 to putting the device on over the head to afford freedom, and it also serves when the upper portion of the garment is positioned above the breasts to hold said portion under tension so as to enable it to compress and 75 confine the breasts and move the same downwardly and hold them in such state when the device is drawn downwardly and secured about the body. It will also be noted that the defined arrangement of the lower 80 tabs 7 relative to the upper tabs 6 affords an opening at the back which renders the device cool and comfortable, and that said arrangement also enables the user to draw the device 85 downwardly and tight about the body. 90

At a point opposite the reinforcement or reinforced dart 5, the body portion 1 is preferably provided with a loop 8, designed for the passage of at least one of the fastening 95 straps 3 incidental to the adjustment of the garment on the body of the wearer.

It is further to be noted that my novel garment is simple and susceptible of being cheaply manufactured; is adapted to be put on, and adjusted by the wearer without assistance; and is capable of being used to advantage on a variety of figures.

Having described my invention, what I claim and desire to secure by Letters-Patent, is:

The herein described bust confining and reducing garment comprising a one piece body portion entirely closed at its front and sides and horizontal throughout its upper edge and having upper and lower back tabs 110

extending from said sides and separated by intervening spaces, and also having the ends of the lower tabs free and provided with fastening straps of a length to be drawn and tied in front of the body, an elastic connection arranged immediately below and parallel to the horizontal upper edge of the body and interposed between the ends of the upper back tabs, and shoulder straps con-

nected at their ends to the upper edge of the body at the front and back thereof.

In testimony whereof I have hereunto set my hand in presence of two subscribing witnesses.

MARY V. CLARK.

Witnesses:
